BOAT HULL

Filed June 11, 1929

UNITED STATES PATENT OFFICE

PAUL WETCH, OF WAUKEGAN, ILLINOIS

BOAT HULL

Application filed June 11, 1929. Serial No. 370,119.

My invention relates to hulls of boats and more particularly of motor boats, wherein the bottom of the hull is made with a step to reduce the frictional area of the boat with 5 the water, and my main object is to design the step in sections, some of which may be collapsed to further reduce such frictional area.

A further object of the invention is to construct the collapsible sections of the step in 10 hinged relation to the hull bottom, whereby to change the position of the collapsible sections gradually.

A still further object of the invention is to use lever means for the manipulation of 15 the collapsible sections.

A final but nevertheless important object of the invention is to construct the novel step of few and simple parts which may be operated with ease.

With the above objects in view and any others that may suggest themselves from the specification and claims to follow, a better understanding of the invention may be gained by reference to the accompanying drawing, 20 in which—

Figure 1 is a longitudinal section of a typical boat hull, showing the movable sections of the step collapsed;

Fig. 2 is a similar view, showing the said 25 sections projected or in normal positions;

Figs. 3 and 4 are, respectively, sections on the lines 3—3 and 4—4 of Figs. 1 and 2; and

Fig. 5 is a sectional view similar to Figs. 3 and 4, showing a modification.

Referring specifically to the drawing, it is seen that the boat hull 10 is made with the usual step 11, the same having a frontal transverse reinforcement 12 and longitudinal reinforcements 13, the latter being preferably 40 perforated as indicated at 13^a to permit the passage of water and air and therefore lessen the resistance of the craft to the same.

Instead of having the step 11 extend in a single body from side to side, I choose to 45 divide the same in the main embodiment into two laterally-spaced sections, as more clearly shown in Figures 3 and 4. Between the sections of the step I insert a separate filler section 14 of similar design, except that instead of being rigid, the section 14 is hinged

to the cross member 12 as indicated at 15, so that it may rise as in Figures 1 and 3 or drop to the level of the step 11, as per Figures 2 and 4. In the latter event, the limit of motion is provided by tongues 16 which extend laterally from the section 14 to abut the sections 11, as clearly shown in Figure 4, so that the three sections are even and to all intents and purposes the step is in the conventional or normal form.

The full step, as was last mentioned, is of advantage when the craft is stationary or is set in motion; however, when speed is being gained, the lifting of the section 14 of the step removes a corresponding frictional area from contact with the water enabling the craft to gain in its progress and show better speed. When it is considered that a comparatively small gain in speed is of advantage during contests of speed boats or when a boat 70 is compared for purposes of sale, the fact that I am able to improve the performance of the boat by the novel change in construction is of vital importance.

For the purpose of raising or lowering the movable section 14, I have chosen a simple lever 17 pivoted at 18 to the hull and operating a link 19 which is connected to the section, a rack 20 serving to station the lever at chosen points. This is but one means of controlling the step section, and I do not wish to limit myself thereto as various other means may be employed for the purpose.

The drawing also shows the tail portion 21 of the hull provided with a movable insert or filler 22, which is operated in the same manner as the step filler at the front. This application is illustrated to show that I can employ the same principle at both ends of the hull to reduce friction thereat. In case 90 the division of the step into but two sections is objectionable, such as where the width is excessive, the step may be divided into several sections, as shown in Figure 5, the movable sections 14 being arranged therebetween and operated along the same lines as in the main embodiment. Figure 5 shows the movable sections collapsed similarly to the showing in Figure 3, and it will be seen that in case of a wide hull, the sections of the step may be 100

made more firm by this modification. Also, a greater cumulative area of the step may be collapsed from friction with the water.

It will be seen that my improvement is one of extreme simplicity and can be made with sufficient strength to operate with efficiency and durability for long periods. By proper control, the boat may be put under way with the full step and tail supported on the water, and to gain speed the movable sections of these parts may be gradually collapsed until the boat rides on the minimum area of its bottom consistent with safety.

I claim:

1. A step for boat hulls having a section collapsible toward the hull, and intercepting stop means for said section carried by the hull and arranged outwardly of said section and in the path thereof, said section providing a transverse air and water passage across the bottom of the hull.
2. A step for boat hulls composed of laterally grouped sections, some of these being collapsible to reduce the contact area of the step with the water surface, lineal supports for the non-collapsible sections, and said supports having transverse air and water passage openings therethrough.
3. A step for boat hulls including a section horizontally hinged at the front and collapsible toward the hull, rigid stop portions carried by the hull, and arranged to intercept said movable section to limit outward movement thereof.
4. A step for boat hulls including a section horizontally hinged at the front and collapsible toward the hull, and means to adjust the hinged section at different points in its swing, rigid stop portions carried by the hull, and arranged to intercept said movable section to limit outward movement thereof.

In testimony whereof I affix my signature.

PAUL WETCH.
